(57) **CLAIM**

The ornamental design for a monitoring device, sensor unit, and band, as shown and described.

DESCRIPTION

FIG. 1 is general view of the monitoring device, embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof;

FIG. 8 is general view of the sensor unit, embodying the new design;

FIG. 9 is another general view thereof;

FIG. 10 is a general view from the bottom thereof;

FIG. 11 is a top view thereof;

FIG. 12 is a bottom view thereof;

FIG. 13 is a right side view thereof;

FIG. 14 is a left side view thereof;

FIG. 15 is a back view thereof;

FIG. 16 is a front view thereof;

FIG. 17 is general view of the band, embodying the new design;

FIG. 18 is a top view thereof;

FIG. 19 is a bottom view thereof;

FIG. 20 is a right side view thereof;

FIG. 21 is a left side view thereof;

FIG. 22 is a front view thereof; and,

FIG. 23 is a back view thereof.

The broken lines if present in the drawings are for illustration purposes only and form no part of the claimed design.

1 Claim, 14 Drawing Sheets
